WILLIAM F. MESERVE AND FORREST C. MESERVE, OF SALEM, NEW HAMPSHIRE

SNOW-REMOVING DEVICE

Application filed October 12, 1926. Serial No. 141,178.

This invention relates to machines or apparatus for clearing roads of snow-material. Such material varies in consistency from light new fallen snow through all gradations of compactness to glaciated snow. The general purpose is to remove such material from highways, and to deliver it along the sides thereof, or into trucks or other vehicles in which it can be carried away. To serve this purpose practically and efficiently, we have invented and will herein describe a machine adapted to operate upon all grades of snow material without liability to stalling or clogging, requiring for the most part only control and regulation of its locomotion as a whole in order to adjust the forward feed of the material-removing factors to varying consistency of such material.

We are aware that push ploughs and rotary ploughs have been used in connection with tractors and motor trucks, and we are aware that endless belt lifting devices have been used in connection with runners and geared to the propelling motor of a truck. The essential mode of operation of our invention, with respect to the actual separation of snow material from the mass lying on a road is markedly different in kind from that of either a push plough or rotary plough; and although our instruments for detaching such material from the mass are, in the specific illustrations here presented, availed of to perform a function analogous to that of endless belt or bucket conveyors, this auxiliary function is collateral to their chief and characteristic function and performance in respect to the removal of material from the road-mass.

Snow, especially if wet and compacted, tends to stick to objects thrust into or against it with relatively slow movement, and correspondingly high pressure, such as plough blades and deflectors, scooping buckets, or conveying tubes such as are associated with rotary ploughs. We have found that by using an independent high speed motor to drive long, horizontal, narrow blades at great speed of attack upon the accumulated snow-material while the machine as a whole is moved forward at relatively low speed a thin

layer of snow material is picked off by each blade in its transverse across the face of said material, and can be carried to a cross conveyor running at high speed, by which it is shot out clear on the side.

In our pending application on the Snow removing automobile, Serial No. 680,369, filed Dec. 3, 1923, we show a construction in which the snow-material cutting blades are placed in front of the radiator and of the front steering wheels. Objection to this construction however is that where it is necessary to turn, the assemblage of cutters on their endless carrier moves sidewise through a long arc at the forward end. In this present device therefore we use front driving wheels and rear steering wheels whereby the front wheels are always moving directly behind and in the same direction with the endless carrier and the series of blades thereon. In the apparatus shown in the said application the blades have a pronounced curved cross-section, which if literally adopted would tend to collect and become clogged with snow-material and would be imperfectly adapted to discharge said material centrifugally during their rotative movement around the narrow end of the carrier frame, although for purposes of picking or slicing off snow-material from a mass on the road the forward inclination of such blades, though extreme as shown, is not ill adapted.

We therefore prefer to use in place of such pronounced curved blades slightly curved or even flat faced blades which in operation travel at great speed and thus attack the snow-material incisively, picking it off in thin layers, producing a multitude of fragments, and thereafter, on passing over the upper end of their rotative traverse, fling it off centrifugally and forcibly so that the snow-material is thrown clear away, leaving the blades clean.

To secure a sensitiveness in operation and the instantaneous control which we find is necessary in a device of this kind, which must be used in hard as well as soft snow, and which is likely to strike sections of glaciated snow which may be substantially solid ice, we provide an adjustable governor to control the speed of a high speed motor which is en-

tirely independent of the main propelling motor and operates the endless chain of horizontal cutter blades and their carrier which extends out forward and is of a width preferably greater than the gauge of the wheels.

With this governor in connection with a slipping clutch of the usual type and the usual throttle, clutch, and gear shift, together with the usual brake, the operator instantly senses 10 an inseparable obstruction and can stop his vehicle propelling mechanism or slow it down as may be necessary. The slipping clutch prevents any smash up.

Snow material removing outfits of this kind must be capable of attacking deep drifts well packed, and also to work down close to the ground.

Our various endless chain type carriers, including that for the snow-material slicing 20 cutters and the collecting carrier and the discharging carrier, preferably all have substantially flat faced blades instead of deeply curved or pocket type, and these blades pass down under and then up over an apron, thence 25 down over and around the end of the apron at such high speed that the snow material is thrown clear by centrifugal force at the delivery end.

This construction and high blade-velocity 30 used on the endless chain system of blades which constitutes the instrument for attacking and removing snow-material from the mass on the roadway, and, in the machine herein described functions also as an elevating carrier allows the blades to be adjusted 35 so as to work very close to the ground. Their high speed will not allow any lumps to form, or any snow-material to adhere to, pack against, and eventually clog the blades. The 40 rotative speed of the endless carrier and the snow-material removing blades required both to keep the blades clear and unclogged, to attack the snow-material in such manner as to preclude any compacting effect on said 45 material and thereafter to throw the material forcibly away from the blades, is of course a variable within limits which, though practically real and discernible, are not susceptible of precise quantitative statement. If 50 the velocity imparted to these blades be high enough to pick off successive thin layers of glazed snow it will be amply adequate to operate on less compact snow-material. We 55 have demonstrated in practice that a velocity between six and eight hundred feet per minute enables the snow-material removing 60 blades to attack such material in all grades of compactness or solidity likely to be encountered, without jamming or stalling, packing or clogging, and to discharge said material after removal from the mass on the 65 roadway so as to keep the blades clean and clear of the material for succeeding operation on the mass. The high speed impact 70 attack of the blades on the snow-material is

radically different in its effect from the slow advance of a push plow or scrapers rigidly attached to and moving with the locomotive vehicle, which not only requires very powerful locomotive effort, but is ineffective if 75 glaciated snow is encountered, either riding over it, or jamming if it penetrates it.

In the drawings, Fig. 1 is a side elevation partly in section, showing our machine.

Fig. 1a shows blades having a pronounced 75 curvilinear cross section.

Fig. 2 is a plan also partly in section.

Fig. 3 is a sectional elevation from the left on the line 3—3 of Fig. 2, or looking in the direction of the arrows.

Fig. 4 is a diagrammatic plan showing the driving means.

Fig. 5 is a detail of the governor and carburetor.

Fig. 6 is a detail of the carburetor and governing valve.

Fig. 7 is a diagram showing another arrangement of our snow removing unit used in a different way.

Fig. 8 is another diagram showing still 95 another way of using our snow removing unit.

In the drawings, the principal features of our device include a propelling unit which includes the usual automobile chassis or 95 frame A of any standard motor truck, carrying the motor B and having what would ordinarily be the rear wheels, but in this construction are the front wheels C, driven by a suitable connecting shaft from motor B, 100 and the rear wheels D which would be ordinarily the front wheels, by which the unit is steered. This is shown as having the usual controls, to be described more in detail later.

The other part of the device is the snow material removing unit which includes the frame or frame work F which carries an independent high speed motor H the speed of which is controlled by the governor G and which controls the movement of the several 110 endless chain type carriers, namely carrier K on which are mounted the horizontal transverse blades 84, the collecting carrier L and the discharging carrier M. The two latter are auxiliary to the carrier K and its blades 115 84 which make initial attack on snow-material lying on the roadway as they pass from below up around the forward sprockets 82, then on emerging from the snow-material, (which they continue to slice off as far up as the mass to be encountered extends) function intermediately as elevating scrapers or flights, and thereafter, on passing over the narrowed sprockets 81 fling the snow-material centrifugally backward and downward 120 to the collecting carrier L.

Preferably the construction of K, L and M includes an apron of wood or metal or other smooth material over which the endless chains cause the blades to pass carrying the snow 125

with them, discharging it when they pass by the sprocket wheels which carry the chains.

The main propelling frame or chassis A 5 may be of any standard type which it is not necessary to describe, and preferably includes the house or housing 10 having the window opening 11.

2 represents the gasoline tank and 1 represents the usual steering wheel which we prefer to disconnect entirely when the snow loading attachment is in place.

13 represents the steering post, 14 the brake pedal, 15 the hand or emergency brake, 16 15 the gear shift and 17 the clutch.

These are all connected to the elevated controls within convenient reach of the driver on the operator's seat 44 in the operating gallery 42 approached by a ladder 43, all carried 20 by the floor 41 and floor beams 40 comprising part of the snow removing unit frame F.

The throttle 20 is connected by suitable rods not shown with the motor B whereby the gasoline supply can be governed from the 25 seat 44.

The steering wheel 23 is carried by vertical post 123 having at its lower end a gear which meshes with another gear on horizontal steering rod 3 which engages a suitable gear 30 on steering post 13 whereby the rear steering wheels D and D are turned.

The foot brake pedal 24 by means of a wire rope 124 which passes over suitable guides connects with the extension 4 on brake 35 pedal 14 thereby controlling it, and the gear shift lever 16 is moved by a rod 6 loosely and slidably pivoted at 46 and connected to the lower end of elevated gear shift lever 26 pivoted at 126 on gallery 42 whereby the 40 gears may easily be shifted from the driver's seat.

The clutch pedal 27 is similarly connected by means of rods 127 and 127 with the regular clutch pedal 17.

45 The high speed motor H is of any usual explosive engine type having a self-starter or crank 51, a clutch and clutch lever 55 and gear shift 56 as shown in Fig. 3. The motor is supplied from the additional gas tank 50, 50 through pipe 53 which passes into carburetor S having a butterfly valve or governor throttle shutter which can be opened and closed by means of the governor G.

This governor may be of any usual type, 55 the one shown being of the locomotive type with the toggle joint action and centrifugal balls or weights 317.

In this particular governor, 301 is the governor lever housing and 302 the cap while 60 303 is the lever, 304 the fulcrum pin, 305 the thrust plug, 307 the adjusting screw by which the speed desired can be regulated.

308 is the carburetor intake pipe, 309 the governor throttle shaft plug, 310, 311, 312 65 the parts of a rack spring plug, 310 is the

plug, 311 the spring and 312 the rack of such a governor, 313 the lever push rod, 314 push rod tube, 315 bushing and 316 the weight block. 317, 317 are the weights, 318, 318 their pivot pins, 319 the plunger, 320 the spring and 321 the spring cap.

This particular governor is operated from the water pump, the body of which is shown at 322 the water pump body 322 has bearings for water pump shaft 327 which carries gear 323 in which are pivot pins 318, 318, whereby the speed of water pump shaft 327 controls the outward throw of governor weights 317, 317, and therefore the movement of plunger 319 and the various parts to rack 312.

308 is the carburetor intake pipe and located in this is a butterfly valve or governor throttle shutter 324 carried by shaft 325 which carries a gear 326 in engagement with regular governor throttle rack 312.

The gasoline feed pipe 53 enters carburetor float chamber 330 while 331 is the carburetor barrel and 332 the carburetor butterfly shaft and 333 carburetor butterfly valve.

The governor G is set by means of a screw 307 so that as the speed of water pump shaft 327 increases or decreases, it operates the governor throttle shutter 324 thereby giving the high speed motor H a uniform speed regardless of the load.

The forwardly projecting carrier K includes a frame 70 pivoted at the top 71 and capable of being raised or lowered by means of the links 72 attached to the pivoted arms 73, 73, to which are connected ropes 74 which wind around a rod 75 controlled by a handle 76 and capable of being held in place by a ratchet 77.

The carrier K includes an apron 80, top sprockets 81, 81, and bottom sprockets 82, 82, over which run the chains 83, 83, between which are the scrapers 84, 84. These chains and sprockets are driven by means of the sprocket shaft 85 which carries a sprocket 86 driven from sprocket 87 on shaft 88 by means of chain 89.

the chains 92 running over sprockets 93, 93 and 94, 94, driven by means of a shaft 95 carrying gear 96 which engages gear 97 on shaft 195.

5 The discharging carrier or truck loader M is pivoted to the side frame under the end of the collecting carrier L and includes the side frames 100, 100, between which is fixed the apron 101 over which travel the cross slats or 10 scrapers 102 carried between the chains 103 and 104 which run over sprockets 105, 105 and 106, 106, these being driven from shaft 207 which carries sprocket 107 around which passes chain 108 driven by sprocket 109 on 15 the same shaft with gears 110 which engages gear 111 on shaft 197. We prefer to use the clutches with suitable levers 115 for connecting or disconnecting the collecting chains and 116 for connecting or disconnecting the dis- 20 charging chains.

We prefer to use the curved deflector R opposite the rearward discharge end of the carrier K over collecting carrier L.

We also prefer to use a deflector wing P 25 pivoted at the outer or upper end of the loader M so as to direct the snow downward instead of allowing it to be shot off sideways when the device is to be used for loading trucks.

This deflector can be controlled by means 30 of a rope 120 passing over a suitable pulley to a suitable cleat 121 and the loader can be raised and lowered by means of ropes 124 and 125 passing over suitable pulleys to a winch 126 which can be turned by hand and 35 locked in place by a pawl 127.

The provision of a high speed motor, (independent of the vehicle locomotor) and consequent high velocity of the blades 84 and the fact that the sector of their rotative path 40 in which initial attacks on snow-material is made, is in the van of advance of the entire apparatus, and spans a width at least equal to and preferably exceeding the tread-width or gauge of the vehicle, are important for the 45 following reasons.

First: The high velocity with which the blades 84 successively attack the opposed face of the snow-material mass restricts the depth or section of material which each blade can 50 sever from the mass to a small dimension, and the sharp impact of the blade's edge knocks or picks off the material from the mass rapidly, preventing it from sticking to the blade—if the material be light or discrete snow—, 55 or from checking or stalling the blade and endless carrier—if the material be glaciated and substantially concrete or solid. The discrete character of the thus removed material, whether snow or shattered ice, is demonstrated by the condition in which it is centrifugally discharged at the rearward sprocket end of the carrier, where it is thrown off as a cloud of particles.

Second: The high normal speed of the carrier L and its blades 81, is substantially uni-

form; the rate at which snow-material is severed from the mass on the roadway may be governed by the operator's regulation of the vehicle motor; should he be inattentive when a stratum of heavier material is encountered, 70 the slip of the clutch will warn him, and at the same time guard the apparatus against injury.

Third: As the thus cooperant carriers are driven in train from the high speed automatically governed motor, their several capacities will always be in proper mutual relation.

Fourth: The blades, as 84, which make the initial attack on snow-material, being at least 80 as long as, and preferably longer than, the overall width of the apparatus (with the exception of such parts as the discharging carrier M, which is too high to encounter any parts of piled or drifted snow) the snow-material removing blade system will prepare a path, cleared practically to ground, in which the advancing vehicle can easily progress.

As shown in Fig. 7, the snow removing and loading apparatus comprising the frame F, 90 motor H, governor G, snow-removing elevating carrier K and collecting carrier L might be mounted on the rear end of an ordinary truck such as 151 from which it might be readily detachable or attachable without altering the body.

In this case, the driver 150 would be facing to the rear but could be provided with a mirror 152 in which he could see the signals of another operator 153 standing on the ground, 100 and by suitable signalling he could move faster or slower, stop or turn or do whatever he was directed to do in a manner similar to the method in use in the pilot house on the old time steamships, having a speaking tube. 105

As shown in Fig. 8, a similar unit such as F, G, H, K, L, mounted on wheels 134, by means of couplings 130 might be attached to the front of a propelling unit 141 in which the operator 140 would be facing to the front. 110 By means of two mirrors 132 and 133 on the principle of the periscope, he could see ahead over the top of the lifting carrier and guide himself to a certain extent although he might be assisted by signals in a similar manner to that shown in Fig. 7.

With my snow removing unit with its independent motor and governor, there is no slowing down because the propelling speed is reduced. By adjusting the governor, the 120 desired operating high speed may be adjusted, and this does not change whether the whole machine is advancing at the rate of one foot a minute or ten feet a minute.

We claim:

1. In a machine for clearing roads of snow-material, a locomotive vehicle, a travelling series of blades projecting in advance from the vehicle, said blades horizontally spanning a distance not substantially less than the 125

greatest overall width of the entire apparatus with their sector of attack on material to be cleared in the van of advance of the apparatus, each and all of said blades being formed to act as combined ice cutters and conveyors, a motor carried by the vehicle and geared to the travelling series of blades to impart thereto a velocity of attack upon said material adapted to shave the ice and 10 remove successively thin layers from the mass.

2. In a machine for clearing roads of snow material, a locomotive vehicle, an apron mounted on and projecting in advance from the vehicle, a series of horizontal transverse blades each and all of said blades being formed to act as combined ice cutters and conveyors, a carrier therefor of the endless chain type, sprockets at the forward and rearward 15 ends of the apron, said blades horizontally spanning substantially the entire width of the apron, the width of the apron being not substantially less than the greatest overall width of the entire apparatus, the sector of attack 20 of said blades upon said material to be cleared in the van of advance of the apparatus, a motor carried by the vehicle and geared to the said blade carrier to impart to the blades a velocity of attack upon said material adapted 25 to shatter the same and remove successively thin layers from the mass.

3. In a machine for clearing roads of snow material, a locomotive vehicle, an apron mounted on and projecting in advance from the vehicle, a series of horizontal transverse ice cutter blades, a carrier therefor of the endless chain type, sprockets at the forward and rearward ends of the apron, said blades horizontally spanning substantially the entire width of the apron, the width of the apron being not substantially less than the greatest overall width of the entire apparatus, the sector of attack of said blades upon 35 said material to be cleared in the van of advance of the apparatus each and all of said blades being formed to act as combined ice cutters and conveyors, a motor carried by the vehicle and geared to the said blade carrier to impart to the blades a velocity of attack upon 40 said material adapted to shatter the ice and remove successively thin layers from the mass, said cutter blades serving to convey the material rearwardly and to throw it centrifugally from the blades as these pass over the rearward sprocket.

4. In a machine for clearing roads of snow material, a locomotive vehicle, an inclined endless series of cutter blades projecting in advance of the vehicle and pivotally suspended adjacent its upper end whereby said inclined series of cutter blades hangs pendant with its lower end adjacent the ground, means connected to said lower end for adjustably supporting the same and adjusting its elevation from the ground, the sector of at-

tack of said endless series of blades being in the van of advance of the apparatus, said cutter blades being of a length to substantially span the greatest overall width of the entire apparatus and each blade being dished, and a motor carried by said vehicle and geared to said series of blades to impart thereto a velocity of attack upon ice sufficient to cut or shave the same and remove successively thin layers from the mass.

5. In a machine for clearing roads of frozen material, a locomotive vehicle, a travelling series of cutter blades projecting in advance of the vehicle, said cutter blades horizontally spanning a distance not substantially less than the greatest overall width of the entire apparatus and being curved in cross section, a motor carried by the vehicle and geared to the travelling series of cutter blades to impart thereto a velocity of attack upon said material sufficient to shave or shatter the same and remove successively thin layers from the mass to discharge the same by centrifugal force, a driver's station located behind the discharge end of said travelling series of blades, and shield means disposed in front of said driver's station to deflect centrifugally discharged material from said driver's station.

6. In a machine for clearing roads of frozen material, a locomotive vehicle, an inclined endless travelling series of cutter blades projecting in advance of the vehicle, each and all of said cutter blades being of dished cross section, means for operating said travelling series of blades at sufficient velocity of attack upon the frozen material to shatter the same and remove successively thin layers from the mass, an elevated driver's cab located behind and adjacent the upper end of said inclined series of blades, said cab having a sight opening directly above the upper end of said inclined series of blades, and a shield located at the upper end of said inclined series of blades to deflect the centrifugally discharged material from said sight opening.

7. In a machine for clearing roads of frozen material, a locomotive vehicle, a travelling series of cutter blades projecting in advance of the vehicle, said cutter blades horizontally spanning a distance not substantially less than the greatest overall width of the entire apparatus, and each blade being curved in cross section, a motor carried by the vehicle and geared to the travelling series of cutter blades to impart thereto a velocity of attack upon said material sufficient to cut or shave the same and remove successively thin layers from the frozen mass.

8. In a machine for clearing roads of snow material, a locomotive vehicle, an inclined endless travelling series of cutter blades projecting in advance of the vehicle, each and all of said cutter blades being of dished cross

- section, means for operating said travelling series of blades at sufficient velocity to cause them to cut upwardly through snow and ice and rapidly convey it upwardly to discharge the same from the upper end of said travelling series of blades by centrifugal force, and shield means at the upper discharge end of said series of blades to confine and guide the centrifugally discharged material.
9. In a machine for clearing roads of snow material, a locomotive vehicle, an inclined endless travelling series of cutter blades projecting in advance of the vehicle, each and all of said cutter blades being of dished cross section, means for operating said travelling series of blades at sufficient velocity to cause them to cut upwardly through snow and ice and rapidly convey it upwardly to discharge the same from the upper end of said travelling series of blades by centrifugal force, and an arcuate shield disposed rearwardly of the upper discharge end of said series of blades to confine and guide the centrifugally discharged material.
10. In a machine for clearing roads of frozen material, a locomotive vehicle, a travelling series of blades projecting in advance from the vehicle, said blades horizontally spanning a distance not substantially less than the greatest overall width of the entire apparatus with their sector of attack on material to be cleared in the van of advance of the apparatus, each and all of said blades being formed to act as combined ice cutters and conveyors, a motor carried by the vehicle and geared to the travelling series of blades to impart thereto a velocity of attack upon said material to shave the same and remove successively thin layers from the mass and to discharge the removed material from said travelling series of blades, and a conveyor receiving discharged material from the travelling series of blades and geared to said motor to be driven at a speed to discharge material by centrifugal force.
11. In a machine for clearing roads of snow material, a locomotive vehicle, a travelling series of cutter blades projecting in advance of the vehicle, each of said cutter blades horizontally spanning a distance not substantially less than the greatest overall width of the entire apparatus with their sector of attack on material to be cleared in the van of advance of the apparatus, each and all of said cutter blades proper being of dished cross section, and a separate motor carried by the vehicle and geared to the travelling series of blades to impart thereto a velocity of attack upon said material sufficient to cut or shave the same and remove successive thin layers from the mass.
12. In a machine for clearing roads of snow material, a locomotive vehicle, a travelling series of ice cutter blades projecting in advance from the vehicle, each and all of
- said blades proper being of dished cross section and horizontally spanning a distance not substantially less than the greatest overall width of the entire apparatus, a motor carried by the vehicle and geared to the travelling series of blades to impart thereto a velocity of attack upon said material sufficient to cut or shave the same and remove successively thin layers from the mass, and said blades serving to convey the cut material from the place of detachment from the mass to a point remote to discharge such material therefrom by centrifugal force.
13. In a machine for clearing roads of snow material, a locomotive vehicle, an apron mounted on and projecting in advance from the vehicle, a series of horizontal transverse cutter blades, a carrier therefore of the endless chain type, sprockets at the forward and rearward ends of the apron, said cutter blades horizontally spanning substantially the entire width of the apron and being not substantially less than the greatest overall width of the entire apparatus, said cutter blades being of dished cross section with their cutting edges disposed at an angle less than a right angle to said carrier, the apron and blades serving as means to convey material from the point of removal from the road mass rearwardly, and a motor carried by the vehicle and geared to said blade carrier to impart to the blades a velocity of attack upon said material adapted to cut or shave the same and remove successively thin layers from the mass.
14. In a machine for clearing roads of snow material, a locomotive vehicle, an endless inclined travelling series of cutter blades projecting in advance from the vehicle and pivotally suspended adjacent its upper end whereby the weight of the entire series of blades is imposed upon its lower end, means for adjustably supporting the lower end of said inclined series with its sector of attack on material to be cleared in the van of advance of the apparatus, each and all of said cutter blades being of dished cross section and being of a length to substantially span the greatest overall width of the entire apparatus, and a motor carried by the vehicle and geared to the travelling series of cutter blades to impart thereto a velocity of attack upon said material sufficient to cut or shave the same and remove successive thin layers from the mass.
